UNITED STATES PATENT OFFICE.

CHARLES H. WEISGERBER, OF PHILADELPHIA, PENNSYLVANIA.

DESIGN FOR A SPOON.

SPECIFICATION forming part of Design No. 34,747, dated July 9, 1901.

Application filed May 31, 1901. Serial No. 62,676. Term of patent 14 years.

To all whom it may concern:

Be it known that I, CHARLES H. WEISGERBER, a citizen of the United States, residing at Philadelphia, in the county of Philadelphia 5 and State of Pennsylvania, have invented and produced a new and original Design for Spoons, of which the following is a specification.

My invention relates to a new and original 10 design for spoons, and has for its object the production of a memorial souvenir spoon of Betsy Ross, her house, in which the American flag was born, and the history connected therewith, these being represented by symbolic emblems or designs of very ornamental and attractive appearance.

In the drawings, Figure 1 is the front or obverse view of an entire spoon, and Fig. 2 is a reverse view thereof.

As shown in the drawings, the handle of the spoon is provided with the wreath A, forming a medallion, having a portrait B of Betsy Ross. Below the medallion, having their staffs crossed, are the flags C and D, the flag C being the representation of the flag when first made and adopted and the flag D being the flag as it is to-day, representing the growth of the nation. Upon the stem E of the handle are the stars F, which are thirteen in number, 15 representing the number of original States and in the order that they entered into the Union.

At the base of the stem is the representation of a keystone G and the old "Liberty Bell" H upon the face thereof. Below this in the upper part of the bowl I are the coats-of-arms 35 K of the United States, having the streamers or ribbons L flowing from the eagle's bill.

In the bowl of the spoon is the representation of the Betsy Ross house M with the rays of sun. At the top of the bowl upon either 40 side of the keystone are the laurel-leaf N and the oak-leaf N'. Upon the reverse side of the spoon's handle, at the top thereof, is a star O, and the peculiarly oval outlined space P, which surrounds the pictorial representation 45 Q. Below this space is a small shield R, and at the base of the stem, near the bowl, is a torch S, and upon the back of the bowl, at the base of the stem, is the pictorial representation T.

Having thus described my invention, what I claim, and desire to secure by Letters Patent, is—

The design for a spoon, as herein shown and described.

In testimony whereof I affix my signature in presence of two witnesses.

CHARLES H. WEISGERBER.
